UNITED STATES PATENT OFFICE.

ORVILLE G. McMILLAN, OF ALPENA, SOUTH DAKOTA.

ENGINE.

1,349,520.

Specification of Letters Patent. Patented Aug. 10, 1920.

Application filed January 27, 1919. Serial No. 273,442.

To all whom it may concern:

Be it known that I, ORVILLE G. McMILLAN, a citizen of the United States, residing at Alpina, in the county of Jerauld 5 and State of South Dakota, have invented new and useful Improvements in Engines, of which the following is a specification.

This invention has reference to a novel construction of engines of the rotary type 10 and the principal object of the invention is to provide means whereby the engine may be driven in either direction by a simple manipulation of a valve member or said engine may be stopped by setting said member 15 in a certain position.

Another object of the invention is to provide automatic means for actuating the valve member during the operation of the engine in either direction so as to properly 20 control the inlet and outlet of steam therefrom.

The invention also consists in certain other features of construction and in the combination and arrangement of the 25 several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an end view of the invention; 35 Fig. 2 is a side view thereof;

Fig. 3 is a longitudinal section;

Fig. 4 is a cross section;

Fig. 5 is a sectional detail showing the parts in a position to drive the engine in one 40 direction;

Fig. 6 is a like view with the parts in a position to drive the engine in an opposite direction;

Fig. 7 is a like view with the parts in a 45 position to cut off the steam from the engine;

Fig. 8 is an elevation of the valve member;

Fig. 9 is a part sectional view of said 50 member;

Fig. 10 is a cross section through said member;

Fig. 11 is a front view of one end of one 55 of the valve operating rods with the parts detached;

Fig. 12 is a side view of said rod;

Fig. 13 is a sectional view of the means for supporting the inner ends of said rods;

Fig. 14 is a front view of the supporting bracket for said rods;

60

Fig. 15 is an end view of the guiding means for said rods;

Fig. 16 is a side view of such means.

In these views 1 indicates the base of the engine and 2 the cylinder thereof. At the 65 upper part of the cylinder a steam chest 3 is formed which is provided with the inlet pipe 4.

A valve chamber 5 is formed in the wall separating the chest from the interior of the cylinder. A pair of ports 6 and 7 lead from the chest to said chamber and a port 8 leads from said chamber to the interior of the cylinder. An elongated port 9 is formed in the upper wall of the cylinder and this port communicates with the cylinder by the passage 10.

A second elongated port 11 is formed in the wall of the cylinder and this port communicates with the valve chamber by means of the passage 12. The 70 ports 9 and 11 are connected together by the pipe 13, which is outside the cylinder.

A slot 14 is formed in the upper part of the cylinder wall between the ports 9 and 11 and said slot extends entirely through said wall and forms a passage for the sliding head 15.

75

This head is carried by a rod 16 passing through a packing gland 17.

The valve 18 located in the valve chamber consists of the cylindrical body 19 and the stems 20 and 21 which pass through the end 80 walls of the chamber. The cylindrical body 19 is divided into the inlet passage 22 and the outlet port 23 by the substantially semi-circular partition 24. The stem 21 is hollow and forms a continuation of the outlet port 85 23 and this port is connected with the outlet pipe 25.

The cylindrical body 19 is provided with a slot 26 which leads to the outlet port 23. The body is further provided with the inlet port 27 which leads to the passage 22 and is adapted to register with either one of the ports 6 and 7. 28 and 29 are ports at the ends of the passage 22 and adapted to register with the port 8 and the 90 passage 12. 30 is a hand lever connected with the stem 20 of the valve and said lever has a part thereon engaging with the segment 31 whereby said lever will be held in 95 adjusted position.

The piston consists of a drum 32 and an 100

100

105

110

abutment 34, suitably connected with the drum and having the packing members 33 therein. It will be seen the end of the abutment engages with the internal walls of the cylinder. The drum is carried by a shaft 35, the spiders 36, and the ends of said shaft pass through the ends of the cylinder and have keyed thereon the wheels 37. Each of these wheels carries a cam member 38, with which engage rollers 39 journaled on the ends of a yoke 40 which is secured to the rod 16 which carries the sliding head. The yoke slidingly engages the guides 41 which are suitably supported from a stationary part of the engine. The cams are so arranged that the sliding head will be lifted just before the abutment reaches said head and as soon as said abutment passes from under said head said head will be lowered with its end engaging the drum. This end is provided with the packing means 42.

The wall of the cylinder in which the sliding head and the ports 8 and 10 are located is slightly sunken so as to permit the abutment to pass without contacting with this part of the wall. The abutment has its walls rounded so that if it should happen to strike the sliding head it will force said head upwardly out of its way and thus prevent damage to the parts. The walls of the drum immediately on each side of the abutment are slightly concaved, as at 43 so as to prevent the rounded end of the sliding head from striking the drum, as the drum turns under the end of the head and engages said end as soon as the concaved part is moved from under the head.

The means for automatically actuating the valve consists of a pair of levers 44 and 45 of different length and having their inner ends connected with rollers 46 which engage the cams 47 and 48 carried by the shafts 35. The outer end of either one of these levers are adapted to be connected with the hand lever 30 by means of the socket 49 adjustably secured to said lever 30 by means of the slot 50 therein. A spring 51 holds the socket in engagement with the end of the lever as said spring tends to pull the lever toward the cams. Each lever has a part 52 pivoted to its inner end and this part carries the roller 46. This part is also provided with a projection 53. Each of these parts 52 are guided in a bracket 54 secured to one end of the cylinder and springs 55 have their ends engaging a part of said bracket and the projections 53 so as to hold said parts with the rollers 46 out of contact with the cams when the levers are out of engagement with the hand lever 30. The outer ends of the levers 44 and 45 are guided by means of the bracket 56, suitably secured to the end of the cylinder and having guide ways 57 therein for said levers.

The levers are held in neutral position in said guide ways by the springs 58. In this position the levers will not engage with the hand lever 30. When it is desired to engage the levers with said hand lever it is simply necessary to move said levers sidewise against the springs 58 to direct their ends into the socket 49.

When the engine is to be rotated in a forward direction the valve lever 30 is placed in engagement with the lever 44. This will place the parts in the position shown in Fig. 5. The steam will pass from the chest through ports 6 and 27 into passage 22 through port 29 and port 8 into the cylinder between the abutment and the sliding head. This will force the piston to travel in a counterclockwise direction as the pressure of the steam against the abutment will force the piston to rotate. After a certain amount of rotation of the parts the cam will be moved to bring its low part opposite the roller 46 so that the spring 51 will move the handle 30 and the lever 44 toward the cam and thus move the valve to close the inlet ports. As the slot 26 leading to the exhaust port is of greater width than the inlet ports the exhaust will still be open so that the steam and air in front of said abutment will pass through the passage 10 into port 9 and through the pipe 13 into port 11, through 12 and the slot 26 into the exhaust port of the valve. As soon as the abutment reaches the sliding head said head will be raised by the cams, as before described, and as soon as said abutment passes from under said head the same will be lowered and the high part of the cam will again engage with the roller 46 to again move the valve to open the inlet port to the cylinder. This action will be kept up indefinitely. When the engine is to be driven in a reversed direction the handle 30 is placed in engagement with the long lever 45. In this position of the parts the steam will pass from the valve into the port 11 and from this port it will pass through the pipe 13 into port 9 and through passage 10 into the cylinder between the abutment and the sliding head. In this case the exhaust will be through the passage 8 into the exhaust port of the valve. In this position of the valve the steam from the chest will pass through port 7 into port 8 of the valve. When the engine is to be stopped the handle 30 is moved into the position shown in Fig. 7 with the inlet ports cut off so that no steam is supplied to the cylinder. In this position however the exhaust port is still open so that the piston will gradually come to a stop. If it is desired to stop the piston at once the valve is moved to introduce steam in front of the same so that the piston must work against the pressure of the steam. This will stop the piston at once and if the steam is allowed to continue to flow into 125

the cylinder the piston will be forced to rotate in the opposite direction.

In my apparatus the valve is balanced which relieves undue pressure of the valve 5 against its seat. The valve is close to the cylinder so that there is little fall in temperature of the steam in passing from the valve to the cylinder. Sudden changes in 10 temperature are also eliminated and the temperature remains uniform in any one place in the cylinder, thereby reducing heat losses. A greater range of expansion is provided for and a greater range of speed for the same 15 engine, under different loads, may be obtained. All knocking is done away with and water in the steam does not put undue strain on the cylinder or the cylinder head. The 20 quick reverse is an important advantage as is also the neutral position of the parts. The control is very simple and easy to operate. The small rollers standing clear of the hands when not in use will eliminate unnecessary 25 noises. When necessary packing rings may be placed in the ends of the drum but in small engines these rings are not necessary.

It is thought from the foregoing description that the advantages and novel features of my invention will be readily apparent.

I desire it to be understood that I may 30 make changes in the construction and in the combination and arrangement of the sev-

eral parts, provided that such changes fall within the scope of the appended claims.

Having described the invention, what I 35 claim is:—

1. An engine of the class described comprising a cylinder having inlet and outlet ports, a rotary piston in said cylinder, a sliding head coöperating with the piston, means for actuating said head, a valve for 40 controlling said ports, a hand lever connected with the valve for setting the same, a lever adapted to be placed in engagement with the hand lever and means for actuating said lever by movement of the piston for 45 automatically operating the valve.

2. An engine of the class described comprising a cylinder having inlet and outlet ports, a valve controlling said ports, a rotary piston in said cylinder, a shaft connected 50 with the piston, fly wheels on the shaft, cams carried by the shaft, a hand lever connected with the valve for setting the same, a pair of levers actuated by the cams and adapted to be placed in engagement with the 55 hand lever for automatically operating the valve, a sliding head coöperating with the piston, a yoke connected with said head and cams on the fly wheel for actuating said yoke.

In testimony whereof I affix my signature.

ORVILLE G. McMILLAN.
